David Parmele
Letters Patent (Filed March 14, 1830)

The schedule referred to in these Letters Patent, is making part of the same containing a description in the words of the said David Parmele himself of his improvement in the machine for reducing various articles, such as apples for cider, dy woods, bark, for tanning, corn on the cob, and other materials, to a degree of fineness suitable for the several operations.

The following is a specification or particular description of a new & useful machine for, or improvements in the method of reducing various articles, such as apples for cider, dy woods, bark for tanning, corn on the cob &c. by cutting, to a degree of fineness suitable for the several operations & uses for which they are respectively designed, by means of steel, or iron & steel plates so mounted on the projecting edges as to form a series of narrow objects, or cutters, to be inserted longitudinally in the periphery of a revolving cylindrical wheel. The plates are about one inch in breadth, about one eighth of an inch thick, & vary in length from four to eighteen inches, according to the work for which they are intended. The teeth, or cutters, upon the edges of the plates, are about one eighth of an inch wide, & the same width apart, ground with a basal edge like a plane iron, & inserted in the cylinder with the basal in the rear of the motion. These teeth, or cutters, are to be so arranged upon the plates that a tooth or cutter in a preceding plate is followed by a space or interstice in the succeeding plate. The cylinder into which these plates are inserted, may be of wood, ^{having} from twelve to sixteen inches & of length corresponding with those of the plates. It is formed by uniting twelve pieces of wood, well jointed together in the form of a radio, with the grain of the wood forming these radioe, so that the periphery is formed by the ends of the wood; these are strongly bound together by an iron band at each end of the cylinder for which purpose the ends are

to project beyond the ends of the plates, so that the circumference of the cylinder is there so cut down or beformed, as to admit the bands sufficiently within the circumference of the body of the cylinder to permit the keys or wedges which confine the plates to pass in & out of the grooves. For the insertion of the plates, longitudinal grooves of a sufficient depth are cut, and of sufficient width to admit of keys or wedges to be driven by the sides of the plates to keep them firmly, and are susceptible of removal occasions in order to take out the plates, or cutters, to grind or sharpen, to graduate the projection of them to the work, which projection is ordinarily to be about one half inch or an inch. The grooves are so formed as to place the plates about three inches apart and to give a direction to the projecting edges of the cutters, &c. would form an angle of about twelve degrees in advance, in the radii of the cylinder. This cylindrical wheel, so armed with its sharp cutters, receives a rapid revolutionary motion, by means of either edge, or steam, & may be worked by either water, steam, wind, manual, or horse power.

In front of the revolving cutters is placed a hopper or feeding box, so placed as to form an inclined plane, the inclined edge of which approaches so near the edges of the cutters, as nearly to permit them to revolve without coming in contact, from which the apples, dyewood, bark, &c. are fed to the latter.
